UNITED STATES PATENT OFFICE.

NATHAN TOMLINSON, OF CISNE, ILLINOIS.

IMPROVEMENT IN MANURE-DISTRIBUTERS.

Specification forming part of Letters Patent No. 159,476, dated February 2, 1875; application filed October 10, 1874.

To all whom it may concern:

Be it known that I, NATHAN TOMLINSON, of Cisne, in the county of Wayne and State of Illinois, have invented a new and valuable Improvement in Manure-Distributors; and I do hereby declare that the following is a full, clear, and exact description of the construction and operation of the same, reference being had to the annexed drawings making a part of this specification, and to the letters and figures of reference marked thereon.

Figure 1 of the drawing is a representation of a vertical longitudinal section of my manure-distributer, and Fig. 2 is a plan view of the same.

My invention has relation to means for hauling manure and distributing the same in the field; and it consists in combining, with a two-wheel carriage, a removable hopper-shaped body, sliding bottom boards therefor, and revolving spurred shafts, as will be understood from the following description.

In the annexed drawings, A designates a rectangular cart-frame, on which is removably applied a hopper-shaped body, B, the lower flaring portions, B' B', of which are permanently secured in the frame A. D D designate transporting-wheels, one of which is secured rigidly on the axle E, and the other turns loosely on this axle. The axle E and a transverse shaft, F, are arranged in the same plane, and provided with spurs a b, which are adjusted so that the spurs a play between the spurs b. The spurs a and b play between spurs c, which are fixed in the lower edges of the inclined portions B'

B'. C C designate two boards, which constitute the bottom of the body B B', and which are free to slide, one forward and the other backward. G G designate levers, which are pivoted at e e to the upper edges of the flaring portions of the body B, and connected by links f f to the movable bottom-boards C C. The letter O designates the draft-pole, which may be made removable.

By closing the bottom-boards C C, the body B will carry manure without scattering it, and by separating these boards more or less the manure will be scattered, and at the same time disintegrated, by the revolving spikes a and the fixed spikes c.

What I claim as new, and desire to secure by Letters Patent, is—

1. The inclined hopper sides B' B', provided with projections c at their lower ends, in combination with the spurred shafts E and F, revolving in opposite directions, substantially as and for the purpose set forth.

2. The inclined hopper sides B' B', provided with spurs c at their lower ends, in combination with the sliding bottom-boards C C, levers G G, axle E, provided with spurs a, and shaft E, provided with spurs b, substantially as and for the purpose set forth.

In testimony that I claim the above I have hereunto subscribed my name in the presence of two witnesses.

NATHAN TOMLINSON.
